UNITED STATES PATENT OFFICE.

MARSHALL B. LLOYD, OF MENOMINEE, MICHIGAN, ASSIGNOR TO THE LLOYD MANUFACTURING COMPANY, OF MENOMINEE, MICHIGAN, A CORPORATION OF MICHIGAN.

DESIGN FOR A COLLAPSIBLE GO-CART-FRAME ARM-REST.

43,149.

Specification for Design.

Patented Oct. 15, 1912.

Application filed September 6, 1910. Serial No. 580,756. Term of patent 7 years.

To all whom it may concern:

Be it known that I, MARSHALL B. LLOYD, a citizen of the United States, residing at Menominee, in the county of Menominee and State of Michigan, have invented a new, original, and ornamental Design for a Collapsible Go-Cart-Frame Arm-Rest, of which the following is a specification, reference being had to the accompanying drawings, forming a part thereof.

The figure is a view in a side elevation of a go-cart frame showing my new design.

Claim:

The ornamental design of a collapsible go-care-frame arm rest, as shown.

In testimony whereof, I have hereunto set my hand, this 15th day of March, 1910, in the presence of two subscribing witnesses.

MARSHALL B. LLOYD.

Witnesses:

HILDA C. PETERSON,
FRED KRUZEL.
